William Edbert Shoemaker, Freeport, N. Y.

Application June 18, 1942, Serial No. 447,521

21 Claims. (Cl. 126—14)

This invention relates to stoves, and more particularly to stoves adapted to burn charcoal.

The principal object of the invention is to enable charcoal to be conveniently manipulated and disposed of with respect to material being cooked.

A further object of the invention is to enable the heat from the burned charcoal to be applied to the material being cooked in a uniform manner, and furthermore to apply the heat of the burning charcoal to the top, bottom or side, or any combination thereof, of such material.

Another object of the invention is to enable the charcoal supporting means to be mechanically manipulated from relatively remote positions with respect to the bed or beds of coal.

A further object of the invention is to provide a convenient means of igniting the charcoal and for easily extinguishing the same.

Still another object of the invention is to provide a unit having a plurality of beds of charcoal, which are mechanically operable, to be positioned in any convenient manner with respect to one another, and with respect to the material to be cooked, such beds of charcoal being readily manipulated by mechanically operated means controlled by the operator in a simple and efficient manner.

As practiced heretofore, cooking by heat from burning charcoal has been a very unsatisfactory process in spite of the fact that charcoal is capable of producing extreme temperatures, which is often very desirable. As commonly practiced, charcoal burns in a very inefficient manner; the heat given off is generally localized so as to be very unevenly applied. Ignition of the charcoal is relatively slow so that some portion of the bed of coals is apt to be almost completely burned out before other portions are properly ignited.

So far as I am aware, there has been no satisfactory means heretofore for applying the heat from beds of charcoal simultaneously to both sides of an article being cooked, nor has any means been provided heretofore for adjusting the spacing of the beds of coals with respect to each other and to the article being cooked.

Because of the extreme heat of combustion of charcoal when provided with a proper current of air, I have found it preferable to manipulate the charcoal carrying means by mechanically operated devices, which avoid the necessity for use of tongs or other tools.

By this invention I provide also a suitable housing for the entire mechanism, thereby avoid-

ing the usual messy conditions attending the use of charcoal cooking.

Other objects and advantages of the invention will be in part obvious and in part pointed out hereinafter.

In the drawings showing preferred embodiment of the invention and in which similar reference characters denote similar parts:

10 Figure 1 is a front elevation view of the stove with the cover raised and the outer walls removed to show the internal mechanism.

Figure 2 is a side elevation looking from the right side of Figure 1, the outer walls being removed to show the internal mechanism.

15 Figure 3 is a left side elevation of the stove shown in Figure 1, the outer wall being removed.

Figure 4 is a horizontal section of the stove taken along the line 4—4 of Figure 1, looking in the direction of the arrows.

20 Figure 5 is a vertical section taken along the line 5—5 of Figure 4 and Figure 1, looking in the direction of the arrows.

Figure 6 is a section taken along the line 6—6 of Figure 5, looking in the direction of the arrows and showing more particularly a portion of the cover elevating mechanism.

25 Figure 7 is a detailed view of a portion of the mechanism for operating the cover elevating mechanism. The view is taken horizontally along the line 7—7 of Figure 6, looking in the direction of the arrows.

30 Figure 8 is a vertical section taken along the line 8—8 of Figure 4 looking in the direction of the arrows and showing details of the drive and control mechanism therefor for operating the racks for supporting the articles to be cooked. Most of the other mechanism is omitted for the sake of clearness.

35 Figure 9 is a front elevation only of the rack raising mechanism and a portion of the controls therefor.

40 Figure 10 is a plan view of the rack raising mechanism, the section being taken along the line 10—10 of Figure 9, looking in the direction of the arrows.

45 Figure 11 is a front perspective view of the racks removed from the stove and placed in their relative positions.

50 Figure 12 is a detailed view of a nut connecting the elevating screw with the shank of the rack. The view is a section taken along the line 12—12 of Figure 9.

55 Figure 13 is a perspective angular view of the charcoal carrying grills removed from the stove and showing the relative positions for one type of

cooking, the cover of the upper grill being raised to show the internal construction.

Figure 14 is a perspective view of a suitable form of charcoal cartridge.

Figure 15 is a perspective view of another form of fuel cartridge.

Figure 16 is a vertical view, partly in section, of the igniting mechanism and blower mechanism associated therewith, and in addition shows the drain mechanism for ash and water for extinguishing the fire.

Figure 17 is a horizontal section through the ignition means taken along the line 17-17 of Figure 16 looking in the direction of the arrows.

Figure 18 is a vertical section taken along the line 18-18 of Figure 1, looking in the direction of the arrows showing only the upper grate manipulating mechanism, together with its controls, certain portions of the housing and cover being indicated to show the relative arrangement thereof.

Figure 19 is a section taken along line 19-19 of Figure 18 looking in the direction of the arrows and showing only the mechanism for operating the upper grate.

Figure 20 is a section taken along the line 20-20 of Figure 19 looking in the direction of the arrows, and shows details of the drive mechanism thereof and part of its controls.

Figure 21 is a detailed part in vertical section of a portion of the controls for the rack operating mechanism, shown more completely in Figure 8. The view is taken along the line 21-21 of Figure 4 looking in the direction of the arrows.

Figure 22 is a detail of the spit operating mechanism, partly in longitudinal section taken along the line 22-22 of Figure 4 looking in the direction of the arrows.

Figure 23 is a vertical section taken along the line 23-23 of Figure 22 looking in the direction of the arrows, showing details of speed changing gear box for driving the spit and a portion of the mechanism and control for raising and lowering the spit.

Figure 24 is a horizontal section taken along the line 24-24 of Figure 23 showing the raising nut for the spit.

Figure 25 is a horizontal section taken along the line 25-25 of Figure 23 showing the gear shifting lever and associated links and levers.

Figure 26 is a detailed view of a control mechanism for operating the spit raising mechanism shown in vertical section along the line 26-26 of Figure 23.

Figure 27 shows in detail the controlling mechanism and drive for the spit raising mechanism of Figure 26 shown in horizontal section along the line 27-27 of Figure 23.

Figure 28 is a front elevation of the spit raising mechanism and drive and the controls, and includes the controls for the spit rotating mechanism.

Figure 29 is an elevation partly in section of the lower grate and mechanism for oscillating it, taken along the line 29-29 of Figure 4. Indicated above the grate is the spit with its mounting and a fowl impaled thereon.

Figure 30 is a horizontal section taken through the grate along the line 30-30 of Figure 29 looking in the direction of the arrows.

Figure 31 is a vertical section through the lower grate taken along the line 31-31 of Figure 29 looking in the direction of the arrows, and

Figure 32 is a plan view of the table of the stove, the cover being removed.

Referring to the drawings, the stove is adapted to be housed within a suitable cabinet, which in this instance has a framework composed of a base 40 upon which are upwardly extending corner posts 42 supporting a table 44 at a convenient height, about waist high for an operator. Intermediate posts 46 are provided to form with the table 44 and lateral braces 48 a front opening which would preferably be provided with a door (not shown). It is understood that the cabinet will ordinarily be provided with outer walls which might be of sheet metal. They are not shown in this instance as they do not constitute the invention and would obscure the view of the mechanism. At the level of the table 44 is provided a horizontal grill or fire box 50 (hereinafter sometimes referred to as a "grate"), which is intended to receive a charge of charcoal, as indicated in Figure 4, Figure 29, Figure 30 and Figure 32, the charcoal being shown at 52. For this purpose the firebox 50 comprises a rectangular box open at top and bottom with stationary grate bars 54 forming a bottom support for the charcoal (Figure 13). The side walls 56 are adapted to rest upon tracks 58 (Figure 30) upon which the grill slides, as will be described hereinafter.

Below the grill 50 is suitably mounted a box or chamber 60, for the purpose of receiving anything which may drop from the grill. Because of its position, the chamber 60 is exposed to great heat and therefore is also constructed to act as an insulating means to keep the greater part of the heat from affecting mechanism within the cabinet. To this end the box 60 is provided with an inner, preferably sloping, bottom wall 62 (Figure 16) spaced from an outer bottom wall 64 and an outer side wall 66, spaced from an inner wall 68 substantially parallel thereto. Between these walls is inserted a suitable heat insulating material 70, such as asbestos.

The sloping bottom 62 at its lowest point is provided with an outlet 72 fitting into a similarly shaped nozzle 74 of the lower bottom wall 64, to which is attached a flexible conduit 76 leading to a reservoir 78 and detachably attached thereto by a suitable connection 80. Preferably the reservoir is arranged to be removable for the purpose of emptying it and is, therefore, provided with a handle 81 by which it may be carried. Reservoir 78 preferably rests upon the cross member 48 of the cabinet frame and is supported thereby.

Means is provided for initially igniting the charge of charcoal within the firebox 50. For this purpose two perforated pipes 82 are mounted horizontally within the box 60, extending through the end wall thereof and clamped thereto by means of lock nuts 84. Outside of the box 60 the pipes 82 join to a T 86, to which is connected a pipe 88 connected to hand pump 90. A supply of alcohol is adapted to be stored within a tank 92 and is withdrawn therefrom through a pipe 94 and check-valve 96 to the pump 90. The suction of the plunger 98 of the pump 90 draws a charge of alcohol from the reservoir 92 and the pressure of the plunger on its pumping stroke discharges such alcohol through check-valve 97 into the pipe 88 and perforated pipes 82. Preferably the perforated pipes 82 are wound with asbestos 100, partly for the purpose of forming a wick to receive the alcohol and partly for the purpose of insulating the perforated pipes 82. Ignition of the alcohol in the wicking 100 is produced by suitable discharge of electric current across a gap formed by a pair of electrodes 102 mounted adjacent to the pipes 82 on the walls of the box 60.

The lead wires 104 attached to the electrodes 102, lead through a cable 106 to a combination vibrator and spark coil 108 associated by means of the wiring 110 and switch 112 (shown diagrammatically) with a suitable source of electric current 5 (not shown) associated with the mains 114.

Means is provided for initially providing a forced draft to accelerate the combustion of the charge of charcoal within the grill 50. To this end there is provided a blower 116 of any well known type, adapted to discharge through a conduit 118 attached at the orifice 120 in the end wall of the box 60. A suitable source of power is adapted to be applied to a pulley 122 associated with a cone clutch 124 and suitable gears 126 and 128 with the drive shaft 130 of the blower 116. Shaft 130 is suitably journaled in brackets 132 and 134, mounted on a base 136, supported by the corner posts 42 and the upright 46 (Figure 1).

The draft in the conduit 118 is adapted to be regulated by means of a damper comprising a plate 138 slideable in a slot 140 formed between flanges 142 and 144 of the conduit 118. For controlling the sliding of the plate 138 in its slot 140, the end of the plate is provided with a pin 146, projecting downwardly therefrom and adapted to engage the slotted end of a lever 148 formed integrally with an upwardly extending rod 150 extending to the upper table 44. A hand crank 153 is provided to turn the rod 150.

The cone clutch 124 consists of a pair of complementary cone elements 152 and 154 which are adapted to slide into and out of engagement with each other, the latter element being provided with a circumferential groove 156 engaged by yoke 158 pivoted on the base 136 as at 160 and pivotally attached at its other end to one end of a bell crank 162 provided with a pivot 164. The other end of the bell crank 162 is rotatably attached at 166 to the lower end of rod 150 so that as the rod is raised or lowered the yoke 158 is caused to rock backward and forward to engage and disengage the clutch members 152 and 154. The pin 146 is sufficiently long that it will remain in engagement with the lever 148 as the rod 150 is raised and lowered. In order to hold the clutch members 152 and 154 in engagement there is provided a ledge 168 upon which the crank 153 is adapted to rest in its raised position. It will be noted that when in its raised position and turned so as to engage the ledge 168, the damper plate 138 is in an open position. Further opening of the damper may be accomplished with the crank 153 resting on top of the ledge 168.

This invention provides a second firebox or grill 170 (Figure 13) somewhat similar in construction to the firebox 50, being provided with solid side walls 172 and 174 and end walls 176 and 178 and transverse rods 180 at the bottom to support suitable charge of fuel. On the box 170 is provided a cover 182 hinged to the rear side wall 174 and adapted to be held in place by a latch 184 on the front wall 172 adapted to engage pin 186 at the front edge of the cover 182. The cover is adapted to hold the charge of fuel in place while the box is being manipulated as described hereinafter.

Means is provided to manipulate the firebox 170 so that it will assume various positions with respect to the lower box 50. Under some conditions it is desirable that the box 170 be maintained parallel to the box 50 and spaced therefrom as shown in Figure 13, and under other conditions it is desirable to place the box 170 in a more or less vertical position, for instance as shown in Figure 1 and Figure 3. For this pur-

pose, the box 170 is provided with a pair of outwardly extending trunnions 188 mounted on the opposite end walls 176 and 178 which are adapted to engage a pair of arms 190, the ends of the arms being hooked, as shown at 192 so that while the trunnions 188 normally are supported by the arms 190, nevertheless they may be lifted out with the box 170 in a direction generally perpendicular to the length of the arms 190. The arms 190 are mounted on a rigid frame 194 at their other ends and also at points intermediate to their ends. At these points of attachment are provided rollers 198 and 200 respectively, to ride in suitable tracks 196. The rollers 198 and 200 are held in place by and journaled on suitable stud bolts 202. It will be understood that the frame 194 and the arm 190 attached at either side thereof form a rigid structure. Adjacent to the top of the tracks 196 are a pair of guiding cams 204 over which the upper pair of rollers 200 are adapted to roll in such a path that the inclination of the frame 194 and the arms 190 is changed from vertical through all intermediate positions to horizontal, as indicated in broken lines in Figure 18. In the last named position the box 170 rests parallel to the grill 50, in this instance lying directly upon it. Normally the fire box 170 tends to assume a vertical position because the trunnions 188 are slightly above the center of the box sides. As the arms 190 are caused to assume a more horizontal position the box 170 is also caused to follow being tilted by means of a projecting arm 206 mounted at the side of the end wall 176 and engaging one of the arms 190. As the lower edge of box 170 touches the frame 324, the tilted box then tends to lie down upon the frame 324 upon further forward movement of arms 190.

Upward and downward travel of the frame 194 in the tracks 196 is produced by a pair of feed screws 208 provided with nuts 210 spaced from each other by means of a cross member 212 and coupled to lugs 214 on the lower edge of frame 194 by means of links 216 having pivots 218 in the nuts 210 and pivots 220 in the lugs 214.

At their lower ends the screws 208 are journaled in brackets 222 mounted on cross-brace 224. Downward thrust of the screws 208 is taken by collars 225 and the upward thrust is opposed by the bevel gears 226, which are suitably attached to the screws 208. A transverse shaft 228, also journaled in the brackets 222, is provided with bevel gears 230 meshing with the gears 226 so that rotation of both screws 208 is synchronous and in the same direction.

Shaft 228 is also provided with a driving sprocket 232 connected by means of a chain 234 with a sprocket 236 formed integrally with a cone clutch member 238 (Figure 20). The sprocket 236 is adapted to be driven alternatively in either direction and to that end there is provided a second clutch member 239, having a sprocket 240 connected by a chain 242 with a sprocket 244 formed on the clutch member 238. Complementary cones 246 and 248 are provided for the clutch members 238 and 239 respectively, and are adapted to be engaged alternatively by suitable yokes 250 and 252, respectively, of a lever 254 centrally pivoted as at 256 to frame members 258 and 260. Clutch members 238 and 246 are mounted on a shaft 261 provided with a pulley 262 driven by a belt 264 from the pulley 266 of the main motor 268 which is preferably supported on a horizontal cross member 270 of the frame of the cabi-

net. Clutch members 239 and 238 are mounted on and adapted to be rotated by shafts 272 and 261 respectively. Shaft 272 is driven in a reverse direction with respect to shaft 261, by a pair of gears 274 and 276 meshing with each other and mounted on the shafts 261 and 272 respectively.

The pivot shaft 256 of the lever 254 is provided with an arm 278 by which the lever 254 is operated. At its swinging end the arm 278 is attached to a link 280 connecting with an arm 282 mounted on a vertical shaft 284, having at its upper end an arm 286. A link 288 connects arm 286 with a manually operable lever 290 pivoted at its lower end at a rod 292 (Figure 1). The grip 296 is provided for the lever 290.

Means is provided for automatically stopping the raising and lowering of the frame 194 and for this purpose the lever 254 is provided with an arm 300 extending at right angles thereto. At its outer end the arm 300 is connected by means of a link 302 to an arm 304 mounted on a shaft 306 rotatably supported by a bracket 308. Also upon the shaft 306 is mounted a horizontal arm 310 pivotally connected with a vertical rod 312, passing through a hole in a plate 314 mounted on the crosspiece 212. A lower stop 316 is carried by the rod 312 and is of such size as to be unable to pass through the hole in the plate 314. An upper stop 318, preferably a nut threaded for adjustment, is carried by the upper end of the rod 312 and is likewise of a size to prevent passing through the hole in the plate 314.

A pair of racks (as shown in Figure 11) constitute means for performing various functions and, more particularly, for supporting food to be cooked on the grill and for supporting the upper firebox 170. As shown in that figure, the lower rack comprises a rectangular frame 320 intended to be positioned horizontally with respect to the table 44 and provided with downwardly extending legs 322 at either side, by means of which the rack is manipulated. The upper rack consists of a rectangular frame 324, in this instance, of the same size as the lower frame 320, and adapted to register with it. Frame 324 is also provided with downwardly extending legs 326 by means of which it is raised and lowered, as well as supported. Legs 326 differ from legs 322 in that they are mounted at the back corner of the frame 324 so as to clear the lower frame 320. Figure 11 illustrates the general relative position which the racks assume in the stove. The manner in which the racks are supported and manipulated is shown more particularly in Figures 1 to 4, inclusive, and 8 to 12, inclusive.

Referring more particularly to Figures 8 and 9, (which for the purpose of clarification show substantially nothing but the racks and their operating mechanism). The legs 322 are slidable in shoes 328 which prevent tilting of the frame 320. Preferably, the shoes 328 are rigidly attached as by welding to angle irons 330 extending horizontally from front to rear of the frame and attached to the uprights 46. The legs 322 are adapted to be raised by feed screws 332 provided with nuts 334 riveted to the legs as at 336. Screws 332 are supported below by right angle brackets 338 mounted on a suitable cross piece 340 and at their upper ends they are journaled in brackets 342. At their lower ends the elevating screws 322 are provided with bevel gears 344 meshing with bevel gears 346 mounted on a horizontal shaft 348, also journaled in the brackets 338. Rotation of the shaft 348 is produced by mechanism shown in detail, more particularly in Figure 10 and con-

sisting of cone clutches 350 and 352 mounted on shafts 261 and 272 and coupled together with sprockets 354 and 356, respectively, and a chain 358. Cone clutch 350 is also provided with a

5 sprocket 360 which by means of a chain 362 drives a larger sprocket 364, pinned to the shaft 348. Upward or downward movement of the rack legs 322 is produced by means of the engagement alternatively of the cone clutches 350 and 352, which 10 is accomplished by means of the lever mechanism comprising a vertically pivoted lever 366, having a vertical shaft 368 journaled in the cross-pieces 258 and 260, and provided at its lower end with a sidewardly extending arm 370. A link 372 connects arm 370 with an arm 373 on a vertical shaft 374 provided at its upper end with an arm 376 attached by link 378 to a manually operated lever 380. A grip 382 is mounted on lever 380, which is pivoted at its lower end on shaft 292, preferably 15 beside lever 290.

An automatic stop mechanism is provided to automatically prevent the rack 320 from raising or lowering too far. This mechanism cooperates with the clutches 350 and 352 and comprises a lever 384 formed integrally with the arm 366 by which the clutches are thrown into and out of engagement. Actuation of the arm 384 is accomplished by means of a connecting link 386 attached at its other end to a vertical arm of the 20 bell crank 388 (Figure 8), the horizontal arm 390 of the bell crank being attached to a vertically extending rod 392 passing through a hole in one of the nuts 334. An abutment 394 is provided below the nut 334, and a nut 396 is carried by the 25 rod 392 above; thus, as the nut 334 raises or lowers it engages the nut 396 or the abutment 394 to disengage the clutches 350 or 352 respectively.

A similar operating mechanism is provided for the upper rack 324, which is associated with the 30 legs 326. Accordingly, shoes 398 supported by the cross pieces 330 slidably support the legs 326 and vertical feed screws 400 provided with nuts 402 engage the legs 326. Screws 400 are journaled in brackets 404 at their lower ends and at the brackets 406 at their upper ends. Bevel gears 408 at the lower end of the screws 400 engage bevel gears 410 on a cross shaft 412 similar to cross shaft 348 and are actuated by a sprocket 414 similar to sprocket 364. A chain 416 associates the sprocket 414 with a mechanism entirely similar to the unit shown in Figure 10 mounted on the shafts 261 and 272 beside the previously described unit. The front clutch of this unit is 35 shown at 418 (Figure 1) and is actuated by a lower lever 420 (Figure 8) connected by a link 422 to the lever 424 of the vertical tubular shaft 426. At the upper end of the shaft 426 is provided an arm 428 actuated by a link 430 associated with the lever 432 pivotally mounted on shaft 292 and provided with a grip 434. As shown in Figure 9, the lever 432 is positioned between lever 290 and lever 380. Also a stop mechanism for automatically limiting upward and downward movement of the legs 326 comprises a vertical rod 436 provided with lower stop 438 and upper nut 440 adapted to be engaged by the nut 402. The clutch mechanism is actuated through the medium of a bell crank 442 and a link 444 associated with the arm 446 (Figure 1) of the clutch mechanism.

For the sake of compactness, the shafts 374, 426 and 284 are concentrically disposed and for this purpose the two last are tubes and the first is a rod. Their diameters are such that they rest within one another and form bearings for each

other. For the sake of clearness, the diameters are shown greatly exaggerated in the drawings.

For certain types of roasting it is often considered desirable to use a rotating spit. Such a spit is provided by this invention and comprises a pair of parallel pointed rods 450 supported on a pair of cross pieces 452 mounted on a shank 454. Shank 454 is adapted to be supported by and rotate within a hollow head 460 forming the upper end of a cylindrical casing 462. A pair of bevel gears 464 and 466 are adapted to transmit the rotation to shaft 454 from a tubular shaft 468, concentrically disposed within the case 462. Bevel gear 464 is provided with a pin 458 to receive the slotted end of shaft 454 so that the spit is removable. On bevel gear 464 there is a bearing portion 470 cooperating with the bearing 472 at one end of the head 460. The end of the shaft 454, which extends through the bearing end 470 of the bevel gear 464 is provided with a peripheral groove 474 engaged by a keeper 476 pivotally held in place on the end of the head 460 by a stud 478. Bevel gear 466 has a shank end 480 or bearing portion fitting the bearing 482 at the base of the head 460 and pinned to the tubular shaft 468. Casing 462 is slidable upwardly and downwardly in a socket 484 mounted in the table 44, the socket being of such a shape as to receive the head 460 (with the spit removed) in its depressed position as shown in Figure 4. The socket 484 is provided with a hole in its bottom of the approximate cross section of the tubular casing 462 to act as a steady support for that casing. At the lower end of the casing 462 is provided a shoulder 471 having a peripheral groove 473 into which fits a fork 475 by means of which casing is raised and lowered. At the shank end of the fork (Figures 23 and 24) is provided a nut 477 engaging an elevating screw 479. Elevating screw 479 is journaled as at 481 in a block 483 mounted on a horizontal plate 485 and is provided at its lower end with a bevel gear 486, keyed or otherwise suitably attached thereto. A pair of bevel gears 488 and 490 for driving the screw 479 are mounted on stub shafts 492 and 494, respectively, 45 meshed with gear 486 and are adapted to rotate in opposite directions (Figure 27). The stub shaft 492 is journaled in vertical plates 496 and 498 supported by the plate 485, spaced apart to accommodate a sprocket 500, also pinned to the shaft 492. A similar sprocket 502 connected by chain 501 to sprocket 500 is provided with a tubular stub shaft 504, journaled in the plates 496 and 498 is keyed to a cone 506 of a reversing clutch (Figure 27). The other cone 508 of the clutch is likewise mounted on a tubular shaft 510, passing through a pair of plates 512 and 513 similar to plates 496 and 498 but on the opposite side of the screw 479. The sprocket 514 is keyed to shaft 510 and connected by a chain 516 to sprocket 518 mounted on shaft 494. Cone 520 is mounted on a shaft 522 passing through the hollow shafts 504 and 510 and is adapted to be driven by shaft 522, there being a key 524 engaging a keyway in the tubular cone 520 which permits endwise sliding of the cone but prevents relative rotation therebetween. Shifting of the tubular cone 520 is produced by means of a yoke 526 pivoted at a lug 528 on the base plate 485 and extending vertically, terminating in a pair of horizontally disposed arms 530 and 532, the former being attached by means of a link 534 to a bell crank 536 pivoted below the table 44 and extending therethrough to terminate in a grip portion 538. The other arm 532 is provided with an upwardly ex-

tending rod 540 passing through a lug 542 mounted on the side of the nut 471. A lower stop 544 and an upper stop 546 in the form of a threaded nut are provided on the rod 540 and are adapted to be engaged by the projection 542 to cause the yoke 526 to be pushed to the right or left (Figure 28) to disengage the clutch.

Means is provided for rotating the tubular shaft 468 and to this end the shaft is provided with a plate 547 welded or otherwise, suitably attached to the bottom of the shaft and having a square hole 548 therein (Figure 24) to engage a square drive shaft 550 adapted to telescope within the shaft 468.

Shaft 550 is adapted to be driven at a variety of speeds and to this end is associated with a change gear mechanism, shown more particularly in Figure 23. The change gear mechanism is supported by a rectangular frame 552 and comprises a shaft 554 journaled in the ends of the frame 552 and having three spur gears 556, 558 and 560 of progressively increasing size in the order mentioned keyed thereto. A shifting shaft 563 parallel to shaft 554 and likewise journaled in the ends of the frame 552 is provided with gears 562, 565 and 566 of progressively decreasing size in the order given, so arranged as to slidably engage the gears 556, 558 and 560, respectively, as the shaft 563 is caused to slide axially, as is understood in the art of change gears.

At the end shaft 550, which extends through the frame 552, there is provided a bevel gear 568 meshing with a bevel gear 570 slidably engaging the shaft 563 as by means of the key 512. Shifting of the shaft 563 is produced by means of a lever 574 (Figure 25) engaging at a rounded forked end 576, the back of gear 562 and a collar 578 serving as abutments. Intermediate its ends, lever 574 is pivoted on a bracket 580 and is controlled from its end opposite the forked end 576 by a lever 582 pivoted at its lower end at a bracket 584 and extending upwardly through the table 44 to position to be grasped by the operator by the grip 586.

The shaft 554 is provided with a bevel gear 594 meshing with a bevel gear 596 on the end of a vertical shaft 598, the driven shaft of a suitable speed reduction unit 600 of any suitable type having a driving gear 602 engaging a driving gear 604, preferably mounted on the end of shaft 261.

As shown in Figure 1, the speed reducing mechanism is mounted on a cross piece 606 between the uprights 42 and 46, and upon the top of this member is mounted the frame 552 of the change speed mechanism. Atop the frame 552 is mounted the base plate 485, also attached to the uprights 42 and 46 to support the clutch for operating the spit elevating screw.

Means is provided for oscillating the grid 50 upon its supporting tracks 58 and for this purpose the grid 50 is provided at one of its end walls 56 with an outwardly extending lug 610 to which is pivotally attached a connecting rod 612 having a crank pin 614 mounted on a rotatable disk 616. Disk 616 forms the head of a stub shaft 618 rotatably supported in the cross piece 620 of the frame and connected by means of a cone clutch 622 to a vertical shaft 624, having a bearing 626 mounted on top of the change gear frame 552. A sprocket 628, pinned to the shaft 624, is coupled by means of a chain 630 to a similar sprocket 632 likewise pinned to the shaft 550. Rotation of the shaft 550 causes similar rotation of the shaft 624. Engagement and disengage-

ment of the cone clutch 622 is controlled by the yoke lever 634, pivoted as at 636 on a cross brace 638 and adapted to be moved up and down by means of an arm 640 extending upwardly through the table 44 and having a cam following portion 642 adapted to slide up and down on the cam 644, mounted on the table 44. Thus as the cam following portion or grip 643 is moved to the right (Figure 29) the yoke lever 634 causes the clutch 622 to engage. A similar motion of the cam 644 to the left disengages the clutch, as will be apparent.

The stove is provided with a cover or hood which serves to enclose the upper part of the mechanism when not in use, and when in its raised position operates to help ventilate and carry off the fumes of cooking. The cover comprises an upper horizontally extending hood 650, preferably of double wall construction, filled with insulating material as shown at 652, between the inner and outer walls 654 and 656. The hood terminates at the rear of the upright section 658 which ends at about the level of the table 44 when in the uppermost raised position. At the lower edge 660 of the upright portion 658 of the cover are mounted a pair of channels 662 extending horizontally and welded or riveted to channel 664 mounted between the inner and outer walls of the portion 658. Channel 662 forms a support for downwardly extending legs 666, having also a lower brace 668. The legs 666 provide a means for supporting the cover 650 from within the main frame of the stove. The legs 666 are adapted to slide within forward and rearward vertical channels 670 and 672, respectively, mounted on the frame of the stove. Upon cross-brace 668 is attached a pair of nuts 674 threaded to engage a pair of elevating screws 676 upon each side of the stove, by means of which the cover is raised and lowered. All of these screws are adapted to operate in unison and to this end they are provided below with bevel gears 678 (Figure 7), those of the forward screws being coupled by means of a shaft 680 having bevel gears 682 meshing with the gears 678, and those of the rearmost elevating screws being engaged by bevel gears 684 on stub shafts 686 having sprockets 688 coupled to sprockets 690 on the shaft 680 by means of chains 692. Suitable bearings 694 and 696 for the shafts 680 and 686, respectively, are provided on the base 698 of the stove. Rotation of the screws 676 is produced by means of a sprocket 700 on the shaft 680 connected by means of a chain 702 with the sprocket 704 mounted on the outer cone of clutch 706 on shaft 261. A corresponding cone clutch 708 is mounted on shaft 272 and is coupled with clutch 706 by means of a sprocket 710 joined with sprocket 712 on clutch 706 by means of a chain 714.

The sliding cones of the clutches 706 and 708 may be operated by a lever 716 provided with an arm 718 by which it is manually controlled. To this end a link 720 connects an arm 718 to a series of levers and links, including bell crank 722, link 724, bell crank 726, link 728 to a manually operable lever 730 pivoted as at 732 on a bracket 734 on the cross brace 736. A safety stop is provided in the form of a rod 738 having upper and lower abutments 740 and 742 respectively, adapted to engage a projection 744 on one of the nuts 674. The rod 738 is attached to a bell crank 746 having a link 748 connecting with an arm 750 operatively attached to the lever 716 by the vertical shaft 751.

For ventilation, a duct 752 is provided formed by a sheet of pressed metal 754 attached to the rear wall of the upright portion 658 and preferably welded thereto, being bent at the lower extremity 756 to register with a circular opening 758 therein. At the upper wall of the cover portion 650 and mounted on the inner wall 654 is a box portion formed by a removable lower plate 760 mounted on a three sided box portion 762 provided with louvres 764 to admit bad air and fumes from below the cover 650. Within the box portion 762 and parallel to it are two parallel rows of pins 766, rather close together, like pickets of a fence, between which is adapted to be stuffed wads of steel wool, or similar material, to act as a filter or strainer to catch grease or solid material drawn through the louvres 764 and into the duct 752.

To provide a draft in the duct 752 a suitable fan 768 is provided in a cylindrical housing 770 formed in this instance integrally with the rear wall 772 of the housing supported by the stove frame. The motor 773 for driving the fan 768 is operatively attached thereto by means of a vertical shaft 774 provided with suitable bevel gearing 776 and 778, the latter being enclosed in a box 780 on the wall 772 and the former being housed in a casing 777.

Suitable fuel to be burned in the grills 50 or 170 is indicated in Figures 14 and 15. In Figure 14 is shown a preferred form in which is provided a cartridge 782 comprising a plurality of chunks of charcoal 784 sawed to substantially the same length and laid with the cracks formed by the grain extending in the direction of the short dimension of the cartridge. The whole may be enclosed in a suitable wrapper 786 such as Cellophane. The object of placing the charcoal in this way is so that upon ignition of the charcoal as much surface as possible will burn simultaneously. In this way the charcoal will be ignited in the quickest possible time and will give off the greatest amount of heat.

Figure 15 is intended to illustrate a cartridge 45 which may be a molded block 788 formed of powdered charcoal with a suitable binder and formed with a great number of perforations 790 extending completely through the chunk. The greater the number of perforations the better, so that as much surface as possible will be burning simultaneously.

In the foregoing, the level at which the cooking operations take place is referred to as the table 44. A plan view of this is shown in Figure 32 with sections shown in Figures 29 and 31.

Referring more particularly to Figure 32, the table comprises an outer rectangle of angle irons 792 and 794, the former being at the sides and the latter at the front and back. Within the rectangle so formed on each side is a pair of angles 796, these being parallel to the angles 792 but spaced therefrom and terminating at the back at angles 798. At their forward ends the angles 796 are riveted or welded to the front angle 794. Interposed between the outer angles 792 and angles 796 are mounted the channels 678 which act as guides for the legs 666 of the cover. Likewise, facing the channels 670 and at the back corners are disposed the channels 672, which are the guides for the rearward legs 666. The space between these angles is clear, permitting the lowering of the portion 658 of the cover into the frame of the stove.

On the inner angles 796 are attached the cams 704 which guide the rollers 198 and by means

of which the upper grill 170 is caused to assume its position in front of or over the grill 50. The channels or guides 196 are attached to the angles 796 immediately behind the cams 204.

As shown in Figure 31, the elevating screws 208 are guided by bearing blocks 800 attached to the back of a cross brace 802, suitably mounted between the cams 204.

Forwardly and between the angles 796 at the left (Figure 32) is mounted a casting 804 to receive the head 460 for supporting the spit. A slot 806 provides a guide for movement backward and forward of the lever handle 588 for operating the chain gear mechanism.

Directly in front of the casting 804 and between the angles 796 is mounted a plate 808 upon which is mounted the bell crank 536 operated by the handle 538. The space to the rear of the casting 804 bounded by the angles 796 and 798 is covered by a suitable plate 310.

At the right hand side, mounted between the angles 796, is a casting 812 provided with a well 814, within which are mounted the levers 296, 434 and 382. Also, in the well 814 is mounted the lever 153 cooperating with the ledge 158 formed integrally with the casting 812. On top of the angles 796 and extending rearwardly to the angle 798 is mounted a plate 816.

Slightly below the level of the plates 310 and 816 (Figure 29) are mounted a pair of parallel angles 818 and 820 extending rearwardly from the front uprights 46, being suitably attached to the cams 204 and the guides 196.

Upon angles 818 and 820 is mounted a plate 822 provided with a rectangular aperture to receive the flange of the box 60 which is supported thereby. Adjacent the edges of the box 60 are mounted the tracks 58 upon which the grill 50 is adapted to slide sidewise. Plate 822 extends rearwardly to the cross brace 824 extending parallel to brace 802 and is attached thereto. Suitable openings 826 and 828 are provided in plate 822 through which the legs 326 of the rack 324 are adapted to pass.

The operation of the stove is as follows:

It will be assumed that initially the upper grill 170 is drawn back to within the stove, the spit has been removed and the supporting head 460 is withdrawn to the position as shown in Figure 4 and that the cover 650 is down on to the table 44 of the stove.

The first operation will be to raise the cover 650 and, accordingly, the lever 730 will be thrown by hand to the right (see Figures 5, 6 and 7). Through the series of levers and links associated therewith (Figure 6 and Figure 7) the clutch 106 is engaged. Electric motor 268 is then started by a suitable switch (not shown). The belt connection 284 and its associated pulley 262 causes rotation of shaft 261 in one direction and shaft 272 in the opposite direction, since they are connected together through the meshing spur gears 274 and 276. Thereupon through the sprocket 704, chain 702, sprocket 700 and shaft 680 the elevating screws 676 are caused to rotate, elevating the cover 650 until the projection 744 on the nut 674 strikes the stop-nut 742, whereupon the rod 738 pulling on the bell crank 746 and link 748 returns the lever 716 to its neutral position, disengaging clutch 106.

The next step will be to build a fire. For this purpose, several cartridges, preferably of the type shown in Figure 14 or Figure 15, are placed in the lower fire box 50. To ignite the cartridges a charge of alcohol is drawn from the reservoir 92

5 by operating the pump plunger 98 and the alcohol is then, by the same pump, forced upwardly through the pipe 88 and pipes 82 on to the asbestos wicking 100.

Alcohol on the wicks 100 is ignited by means of the spark produced by the electrodes 102 connected to the spark coil 108, the switch 112 being used to close the circuit of the spark coil. Flame from the burning of the alcohol ignites the charcoal very readily.

If desired, a forced draft may be produced by means of the blower 116 and controlled by manipulation of the handle 153. As has been described hereinbefore, raising of the handle 153 causes the clutch members 154 and 124 to be engaged, whereupon suitable operation of the centrifugal fan 116 is caused, power being supplied from the motor 268, which is connected to the pulley 122 by the belt 123.

20 Regulation of the amount of draft is controlled by rotation of the handle 153 which causes the damper 138 to open or close the passageway in the conduit 118. It is generally desirable to keep the fan 116 blowing until charcoal of the cartridge in the grate 50 is well ignited, so as to give a substantially uniform temperature throughout the entire area of the grate. It is preferred that after the burning charcoal has been well started, the fan 116 be turned off entirely as it will thereafter be unnecessary or even undesirable for proper combustion.

25 The stove is now in condition for cooking such things as steaks and the like where it is desirable to apply the heat to only one side at a time. For this purpose, the food to be cooked, properly supported by a suitable wire grill or the like (not shown), may be rested on the rack 324. For proper cooking of food, it is desirable to hold the food at a proper height above the fire and provision for this is furnished by the mechanism for raising and regulating the height of the rack 324. Such regulation of the rack 324 is accomplished by suitable manipulation of the manually controlled lever 434. Pushing of the lever 434 toward 30 the back of the stove causes engagement of the clutch 418 which transmits motion from the motor 268 associated with the rotating shafts 272 and 261 through the clutch 418 and associated sprockets and chains to the transverse shaft 412 to turn the elevating screws 400.

35 The nuts 402 which are mounted on the legs 326 of the rack 324 are adapted to travel by the screws 400 within the limits represented by the stops 438 and 440. At the desired height of the 40 rack 324 the lever 434 is returned to its normal neutral position, either by hand or by means of the automatic safety stop mechanism hereinbefore described, comprising the vertical rod 436 connected to the bell crank 442, which in turn 45 operates the clutch operating lever by means of the link 444. Lowering of the rack 324 is produced by pulling the manually operated lever 434 toward the operator, whereupon the motion of the shaft 261 is transmitted through the associated 50 mentioned series of sprockets and chains to the shaft 412 to rotate the elevating screws 400 in a direction to cause the nuts 402 to travel downwardly thereby lowering the rack 324. At the desired height, the manually operated lever 434 is 55 returned manually to the central position as before.

60 For certain kinds of cooking it is desirable that heat should be applied from the side or even from above the food, for this purpose the grill 75 or fire box 170 is used. Normally, this box is

shoved away below the level of the table 44 and at the back as shown in dotted lines in Figure 18. This fire box may be brought to a position where it is superposed upon the lower fire box 52 in the position shown in broken lines in Figure 18, for the purpose of starting the fire to be contained therein. For this purpose the control lever 296 is pushed toward the back of the stove, whereupon, through the means of connecting link 288, vertical hollow shaft 284 and link 280, the clutch comprising the complementary cones 238 and 246 are pushed into engagement causing the rotation of the shaft 261 to rotate the screws 208 through the medium of sprocket 236, chain 234, sprocket 232, shaft 228 and bevel gears 226 and 230.

As the screws 208 rotate, the nuts 210 travel upwardly and through the connecting links 216 pushing the frame 194 upward also along the tracks 196. When the rollers 200 reach the end of the track they ride forward over the guide surfaces of the members 204, and the arms 190, supporting the fire box 170 at its trunnions 188, are inclined forwardly, more or less depending upon the degree of rise of the nuts 210.

For the purpose of starting a fire in the fire box 170, the latter will preferably be carried forward to a position superposed upon the lower fire box 50. In that position the cover 182 may be raised by releasing the latch 184. The fire box 170 is suitably charged with cartridges of charcoal of the type shown in Figs. 14 and 15. The charcoal in the fire box 170 should be readily ignited by leaving that box superposed on the fire box 50. If the heat is found insufficient, it may be increased by inducing a draft by means of the fan 115 as hereinbefore described. If it be desired to start a fire in the box 170 only, charcoal therein may be ignited by alcohol flame as described in connection with the starting of the fire in the box 50. Upon ignition of the charcoal in the upper fire box 170 the lid 182 will be closed and latched as greater draft provided thereby is no longer necessary.

There are several ways in which the fire box 170 can be used. If it is desired to apply heat on opposite sides of the material to be cooked, the fire box 170 may be supported on the rack 324, the separation of the upper and lower fire boxes being adjusted by raising the upper fire box 170 by means of the rack 324 in the manner above described. In this case, as the fire box 170 is raised, the arms 190 remain in their horizontal position as the trunnions 188 lift out of the hooked ends of the arms 190. The material to be cooked is, in this instance, to be supported by the lower rack 320 which is controlled by the manually operable lever 382, which operates the clutch mechanism shown in Fig. 10 for raising and lowering the rack 320.

In many cases it is desirable that fire box 170 should supply heat laterally to the material to be cooked, in which case the fire box is supported in the position shown in solid lines in Fig. 18. Also, the box may be tilted forwardly by a slight movement of the arms 190 to a more inclined position. The tilting is caused by the engagement of the sidewardly extending arm 206, with the adjacent arm 190. Normally, the box 170 tends to stand vertically because the trunnions 188 are positioned slightly above the center of the box 170.

When cooking before the fire, the spit is used. The first operation will be to raise the spit 460 to the proper height with respect to the fire box 75

170. For this purpose lever 538 is operated to throw the clutch mechanism (Fig. 28) into engagement for the purpose of rotating the elevating screw 479. Throwing the lever 538 to the left causes the screw to rotate so that the nut 477 will rise lifting the casing 462 and with it the head 460. When the latter has reached the height desired the lever 538 is thrown back to neutral position. At this point the shank 454 of the spit is inserted into the head 460 and held therein by the detent 476. In this position the fowl or whatever is to be roasted is impaled upon the pointed rods 450 as shown in Fig. 31.

Rotation of the spit is caused by throwing the change gear mechanism into mesh by means of the gear shift lever 582. As has been described above there are three speeds of rotation and three corresponding positions of the lever and its handle 586. The low speed position of the lever is the furthestmost position away from the operator; the high speed position is nearest to the operator and the medium or intermediate speed is between these two positions. The gears are out of mesh at any position between these. Upon shifting the lever 582 to an operating position of the gears, the spit will be rotated. Such motion is transmitted from the gear box by means of the square shaft 550 and its telescoping hollow shaft 468.

30 To return the spit to its non-operative position, it is merely necessary to throw the gears of the gear box out of the mesh by manipulation of lever 582; to disengage the detent 476 to permit removal of the shank 454 of the spit from the casing 480; and, by operation of the lever 538, to engage the clutch of the elevating mechanism so as to lower the casing 460 back into its depression in the casting 804 in the table.

35 The change gear mechanism shown in Fig. 23 serves also to operate the mechanism for shifting the lower fire box 50 along the tracks 58. The object of oscillating this grate is to expose the material to be cooked uniformly to the heat in the fire box. It has been our experience that when material is being cooked over a charcoal grate the heat is apt to be quite uneven for the reason that fat and other material may drop into the grate and by flaring up may cause uneven burning of the charcoal. By shifting the fire box systematically back and forth the heat is evenly applied to the surface of the steak or other material being cooked. The shifting mechanism is controlled by means of the lever 642, which is adapted to control the clutch 620 as hereinbefore described. When the clutch is engaged by throwing the lever 642 to the right, the crank 614 of the connecting rod 612 will push and pull the fire box 50 back and forth at a fairly uniform speed, which may be varied, by means of the change gear mechanism above referred to, to suit conditions.

40 The odors of cooking are carried away through the conduit 752 by the draft produced by the fan 768. As indicated in the drawings, this fan has a separate drive motor 773 which, preferably, operates continuously during cooking. It is understood that a suitable switch (not shown) is provided for operating this motor. The fumes passing into the conduit 752 pass through the louvres 764 and before being passed into the conduit are drawn through the steel wool which is held in place by the rods 766. Grease and condensable material are caught in the steel wool, and for this reason the cover 760 is provided to

permit periodic removal of the steel wool for cleaning or replacement.

As the charcoal burns, any ash formed will drop into the chamber 60 and eventually pass to the container 78. The simplest way to extinguish the fire is to pour water onto it in which case some water and ash also are removed to the receiver 78. On rare occasions the receiver 78 should be disconnected and emptied—not, often because very little ash forms and the water evaporates.

It is understood that many modifications and changes of the above described embodiment will occur to those skilled in the art that will be within the scope of the invention which, however, is to be limited only to the scope of the appended claims.

I claim:

1. In a stove, a support, a fire box mounted on said support and adapted to receive charcoal fuel and the like, a second fire box, means for supporting said second fire box including a pair of arms detachably engaging said second fire box, a guide along which said arms are adapted to slide to advance and retract said fire box to and from said first box, a rack mounted adjacent said first fire box and adjustably reciprocable vertically with respect thereto to lift said second fire box from said arms and to fix the height thereof with respect to the first said fire box when the arms have advanced said second fire box, said rack comprising a rectangular frame horizontally disposed and having vertical legs, and elevating means engaging said legs.

2. In a stove, a support, a fire box mounted on said support and adapted to receive charcoal fuel and the like, a second fire box, means for supporting said second fire box including a pair of arms detachably engaging said second fire box, a guide along which said arms are adapted to slide to advance and retract said second fire box toward and from said first box, a rack mounted adjacent said first fire box and adjustably reciprocable vertically with respect thereto to lift said second fire box from said arms and to adjust the height thereof with respect to said first fire box when the arms have advanced the second fire box, and a second rack to support food and adjustable vertically between the first said fire box and the first said rack.

3. In a stove, a support, a fire box mounted on said support and adapted to receive charcoal fuel and the like, a second fire box, means for supporting said second fire box, including a pair of arms detachably engaging said second fire box, a guide along which said arms are adapted to slide to advance and retract said fire box toward and from said first box, a rack mounted adjacent said first fire box and adjustably reciprocable vertically with respect thereto to lift said second fire box and to fix the height thereof with respect to the first said fire box when the arms have advanced the second fire box, a second rack interposed between the first said fire box and the first rack, each said rack comprising a rectangular frame horizontally disposed and having vertical legs and actuating means engaging said legs.

4. In a stove, a support, a fire box mounted at the upper level of said support, a second fire box, and means on said support to carry said second box from a normal vertical position behind and below the level of said first box progressively vertically upward and forwardly towards first said box and tiltingly to a horizontal position superposed against said first box.

5. In a stove, a support, a fire box mounted at

the upper level of said support, a second fire box, means on said support to carry said second box from a normal vertical position behind and below the level of said first box progressively vertically upward and forwardly towards first said box and tiltingly to a horizontal position superposed against first said box, said means comprising a pair of arms engaging at one end said second fire box, actuating means engaging the other ends of said arms, and track means engaging said arms intermediate their ends.

6. In a stove, a support, a fire box mounted on said support, a second fire box movably mounted on said support, mechanical means to adjust the spacing of said fire boxes with respect to each other while in operative condition, and means to impart continuous horizontal motion to the first box with respect to the second box.

7. In a stove, a support, a fire box mounted on said support and adapted to receive charcoal fuel and the like, a second fire box, power actuated means for carrying said second fire box from a position behind and below the level of the first box to a position above and adjacent first box, and a cover vertically movable on said support to inclose said boxes when the second box is in its rearward and lowered position.

8. In a stove, a support, a fire box mounted on said support and adapted to receive charcoal fuel and the like, a second fire box, carrying means for said second fire box comprising a frame having arms pivotally supporting said second box at their ends, a track extending vertically for part its length and forwardly in the direction of the first fire box for an additional part of its length, for guiding said frame.

9. In a stove, a support, a fire box mounted on said support and adapted to receive charcoal fuel and the like, a second fire box, a pair of arms pivotally connected to said second box for suspension thereof in an edgewise position, an actuating member pivotally connected to said arms, a guide on which said arms are adapted to ride intermediate their ends, said guide being curved to cause the ends of said arms to describe a relatively horizontal non-circular path toward and away from said first fire box and a motor to raise and lower said actuating member.

10. In a stove, a support, a fire box mounted on said support and adapted to receive charcoal fuel and the like, a second fire box similar to the first, and means for transporting said second fire box from a horizontal position above said first fire box to a vertical position below and behind said first fire box including arms pivotally supporting said second fire box at its sides, a guide cooperative with said arms intermediate their ends, said guide having a straight portion and a curved portion extending from the straight portion forwardly and down, and a tilting member on said second box and projecting therefrom to engage one of said arms.

11. In a stove, a support, a fire box mounted on said support and adapted to receive charcoal fuel and the like, an ash receiving chamber below said fire box, torch members in said chamber, a second fire box similar to the first said box, means for supporting said second box above said torch members for igniting the fuel charge therein, including a pair of arms pivotally engaging said second fire box at both sides, a guide along which said arms are adapted to slide to advance or retract said fire box, having a straight portion and a curved portion extending forwardly and down to tip said arms to a position adjacent said first

fire box and actuating means associated with ends of said arms remote from said second fire box.

12. In a stove, a support, a fire box mounted on said support and adapted to receive charcoal fuel and the like, a second fire box, means for supporting said second fire box including a pair of arms at their ends engaging said second fire box, a guide along which said arms are slideable to advance and retract said second fire box toward and from the first said box and a rack mounted on said support adjacent said first box and reciprocable vertically with respect thereto to lift said second box and to adjust the height thereof with respect to the first said box when said arms have positioned the second box over the first box.

13. In a stove, a support, a fire box mounted on said support and adapted to receive charcoal fuel and the like, a second fire box, means for supporting said second fire box including a pair of arms at their ends detachably engaging said second fire box, a guide along which said arms are slideable to advance and retract said second fire box toward and from the first said box and a rack mounted on said support adjacent said first box and reciprocable vertically thereto to lift said second box from said arms and to adjust the height thereof with respect to the first said box when said arms have positioned the second box over the first box.

14. In a stove, a support, a fire box mounted on said support and adapted to receive charcoal fuel and the like, a second fire box, supporting arms for said second box slidably mounted on said support for adjusting the position of said second box with respect to the first box, a spit, and means on said support for driving and adjusting said spit including a vertically extending tubular housing, a shaft within said housing, a hollow head on said housing extending laterally therefrom and adapted to receive said spit, gear means operatively connecting said shaft and said spit, and means to elevate and to rotate said housing with respect to said support and said fire boxes.

15. In a stove, a support, a fire box mounted on said support and adapted to receive charcoal fuel and the like, a second fire box, supporting arms for said second box slidably mounted on said support for adjusting the position of said second box with respect to the first box, a spit, and means on said support for driving and adjusting said spit including a vertically extending tubular housing, a shaft within said housing, a hollow head on said housing extending laterally therefrom and adapted to receive said spit, gear means operatively connecting said shaft and said spit, means to elevate and to rotate said housing with respect to said support and said fire boxes, and variable speed driving mechanism for said shaft.

16. In a stove, a support, a fire box mounted horizontally on said support and adapted to re-

ceive charcoal fuel and the like, a rack on the support for holding food in spaced relation to said fire box and above said box, a guide on the support to receive the fire box and upon which said box is horizontally slideable, a motor and driving connections between said motor and said box to reciprocate continuously the box on the guide.

17. In a stove, a supporting frame, a fire box, members slidably attached to said frame and pivotally supporting said box for adjustment of the position thereof on said frame, a spit, a column on said frame supporting at its upper end said spit, driving connections in said column operatively connected to said spit to effect rotation thereof, and a pivotal mounting for said column at the supporting frame to permit horizontal swinging of the spit with respect to the fire box.

18. In a stove, a support, a fire box for receiving charcoal, means to support said fire box horizontally above said support, and means to transfer said fire box to a vertical operative position with respect thereto comprising a pair of arms, gudgeons on the box engaging the arms, a curved track, fulcrum members on said arms intermediate their length and slideable on the track, an outwardly extending finger on the box to engage one of said arms for tipping said box and means to advance and retract the arms along the track.

19. In a stove, a support, a fire box mounted on said support adapted to receive charcoal fuel and the like, a second fire box, a frame for supporting food adjacent said first box, means to elevate said frame above said fire box, a second frame adjacent said first box adapted to receive said second box, and means to adjust the position of said second frame vertically and independently of the first frame.

20. In a stove, a support, a fire box mounted horizontally on said support and adapted to receive charcoal fuel and the like, a second fire box, a food supporting frame adjacent the first said box, a second frame adjacent the first frame, means for independently adjusting the heights of said frames above the first said box, and means to transfer said second box from a rearward position with respect to the first box to a position overlying said frame.

21. In a stove, a support, a fire box mounted horizontally on said support and adapted to receive charcoal fuel and the like, a second fire box, a food supporting frame adjacent the first said box, a second frame adjacent the first frame, means for independently adjusting the heights of said frames above the first said box, and means releasably supporting said second fire box to transfer said second fire box from a rearward position with respect to the first said box to a position on said second frame.
